CONTAINER

Frank W. Lawson, 114 Jefferson Road, Princeton, N.J.
Filed Mar. 6, 1961, Ser. No. 93,512
20 Claims. (Cl. 220—5)

This invention relates to a container comprising two nestable members capable of interconnection to form a closed chamber, suitable for storing and transporting a large variety of commodities, embodying improvements over copending application Serial No. 3,117, filed January 18, 1960 of which this application may be deemed a continuation-in-part.

Containers embodying the present invention are eminently suited for fluid materials of all kinds including those which are granular as well as those which solidify at reduced temperature. Moreover, these containers are useful for the handling of materials of larger sizes which would not be considered granular or fluid.

The constructions contemplated by the present invention lend themselves to all types of handling including fork lift trucks, pallet trucks, slings, cranes, and all other conventional handling equipment. By virtue of the configurations contemplated by this invention, great economies are achieved in all types of storage and shipment including water transportation involving rates based upon the shipping volume occupied, which is frequently computed on a cubic basis.

It is among the objects of the present invention to provide a container comprising two nestable members each of substantially rectangular cross section and each having side walls extending axially from a closed base to a relatively larger open base, the side walls containing stepped prismatic peripheral sections. These stepped sections preferably have substantially equal dimensions axially of the container and substantially equal dimensions transversely thereof. Each of the open bases preferably terminates in a peripheral rim having an axial dimension substantially equal to that of one of the stepped sections. Each of the stepped sections preferably includes substantially pyramidal wall portions.

The present invention contemplates a container comprising two nestable members each of substantially rectangular cross section and each having side walls extending from a closed base to a relatively larger open base, the open bases terminating in peripheral rims defining cooperating plug and socket members respectively, one of the members containing a peripheral recess and a deformable gasket disposed in the recess and extending peripherally therefrom for sealing engagement with the other of the members. The recess is preferably formed in the plug member and preferably provides a surface composed of rectilinear elements extending axially of the container. The gasket preferably includes a plurality of peripherally extending sealing elements formed of an elastomeric composition.

It is also among the objects of the present invention to provide a container comprising two nestable members each of substantially rectangular cross section and each having side walls extending from a closed base to a relatively larger open base, a substantially rectangular reinforcing flange disposed at each open base, and cooperating clamping members carried by the flanges respectively, the clamping members having interengaging positions lying within a right rectangular prism having a cross section including the flange. The cooperating clamping members are preferably disposed at the corners, respectively, of the flanges and preferably assume the form of cams and levers respectively. The cooperating clamping members are preferably provided with positive locking means and they preferably provide eyes for the reception of hooks or cables for elevating and lowering operations.

2

Containers according to the present invention also comprise two nestable members each of substantially rectangular cross section and each having side walls extending from a closed base to a relatively larger open base, the closed base having corners, and a relatively movable supporting leg connected to the closed base of one of said members adjacent to each of its corners. These legs are preferably adjustable in pairs relative to the closed base to which they are connected and each of the closed bases is preferably recessed in registry with these legs to facilitate stacking and to lend stability to such a stack. The legs are preferably pivotally attached to one of the members and locking means will preferably be provided by the legs and closed base to which they are connected to maintain them in a fixed relative position.

A more complete understanding of the invention will follow from a description of the accompanying drawings wherein:

FIG. 1 is a side elevation of a container embodying the present invention showing the two nestable members assembled in part, one clamping member being in an operative position, another clamping member being in a released position and the supporting legs in their extended positions;

FIG. 2 is a plan view of the structure depicted in FIG. 1 with all of the clamping members in their operative positions;

FIG. 3 is an end elevation depicting the structure as shown in FIG. 2;

FIG. 4 is a fragmentary sectional elevation on an enlarged scale showing three of the members in nested relationship;

FIG. 5 is a fragmentary perspective view on an enlarged scale depicting the clamping structure of the preceding figures;

FIG. 6 is a fragmentary sectional elevation taken along line 6—6 of FIG. 7;

FIG. 7 is a fragmentary plan view illustrating the clamping structure of FIGS. 5 and 6;

FIG. 8 is a top plan view of the leg structure shown in FIGS. 1 and 3 separated from the container members;

FIG. 9 is an exploded perspective view, partially broken away, depicting details of the structure shown in FIG. 8;

FIG. 10 is a fragmentary sectional elevation on an enlarged scale showing the flanges of cooperating nestable members in positions assumed just prior to their assembly or just after partial disassembly; and

FIG. 11 is a fragmentary sectional elevation showing the flanges of FIG. 10 in their completely assembled relationship with the deformable gasket in its sealing condition.

The partially assembled container depicted in FIG. 1 comprises an upper member 20 and a lower member 22, each of substantially rectangular cross section as will be evident from FIG. 2. Each member is provided with a closed base 24, from which side walls 26 and 28 extend axially to a relatively larger open base 30. The side walls contain stepped prismatic peripheral sections 32 having substantially equal dimensions axially of the container and substantially equal dimensions transversely of the container, which dimensions may be identified respectively, as the length of the tread portion 34 of the stepped sections and the riser portion 36 thereof depicted in FIG. 4 and common to each of the sections in order to assure nestability of the members.

By virtue of the substantially rectangular cross section depicted in FIG. 2, departing from the rectangular configuration only at the rounded corners 38, the members constituting a container are substantially prismatic so as to assure a very efficient use of space as compared with drums of cylindrical and other configurations more conventionally employed at the present time. The curved

corners 38 have been employed in the interest of strength, resistance to impact and to render it possible to attach clamping members which will not project beyond the prism circumscribing the assembled container.

The stepped construction of the side walls of the members is designed so that the axial dimension of the tread portion 34 is approximately equal to the vertical nesting clearance of the members in their nested relationship as will be evident by inspection of the lower portion of FIG. 4. This stepped configuration imparts substantially rigidity, produces zones of stiffness, provides a greater volume than would be provided by a straight taper, facilitates die forming of the members, results in work hardening of the material during the forming operation and provides a surface area substantially greater than would be present were a straight draw employed, thereby greatly increasing the heat transfer capabilities of the construction.

It will be noted that the stepped sections include pyramidal wall portions corresponding to the tread portions 34 and riser portions 36 already described.

The open bases 30 terminate in peripheral rims 40, the upper member 20 as shown in FIG. 10, for example, having its peripheral rim in the form of a plug member 42 containing a recess 44 receiving a deformable gasket 46 extending peripherally therefrom for engagement with the internal wall 48 of a socket member 50 provided by the peripheral rim 40 formed on the lower member 22. The axial wall of the recess 44 is composed of rectilinear elements extending axially of the container. Each gasket 46 is shown as providing a plurality of peripherally extending sealing elements 52 and elastomeric materials are preferred for the purpose. When the members are assembled to assume relative positions as depicted in FIG. 11, the peripherally extending sealing elements will be displaced to their sealing positions in engagement with the inner wall of the socket member 50 and in engagement with other portions of the gasket so as to prevent loss of any material within the container and at the same time exclude foreign materials from without. The socket member 50 is shown as terminating in a convergent portion 54 which will serve to guide the plug and socket members into proper engagement during assembly.

It will be noted that the axial dimension required by the plug and socket members together with their gasket appreciably exceeds the transverse dimension so as to economize in the horizontal area requirements of the container during storage and shipment.

The joint provided by the plug and socket members together with their gasket which is preferably both deformable and resilient readily compensates for tolerances in the production of the container components and at the same time assures sealing engagement when they are assembled. This joint construction also compensates for minor deformation due to loading stresses, damage or misalignment in assembly, particularly in the vertical plane. As will be evident from FIGS. 6, 10 and 11, the clearance between the plug and socket members will permit appreciable transverse relative movement.

The peripheral rims 40 defining the plug and socket members are substantially rectangular as will be evident from FIG. 2 and constitute reinforcing flanges at the four corners of which they carry cooperating clamping members having interengaging positions lying within a right rectangular prism having a cross section including the flanges. The lower member 22 to which the lower reinforcing flange 40 is secured by welding or in other suitable fashion carries an abutment 56 containing an opening through which a pin 58 is inserted to define a pivot for a bail 60 having a closed upper end 62 to provide an eye for reception of a cable or hook of the types conventionally used in handling. A roller 64 is carried between the legs of the bail 60 by means of a pin 66 for engagement with the surface 68 of a cam 70 carried by the reinforcing flange 40 welded or otherwise secured to the upper member 20. When the upper member has been applied

to the lower member to define a container as depicted in FIGS. 1 and 3, by elevating the bail from the position depicted at the right side of FIG. 1 to that depicted at the left side, cooperation between the roller 64 and the cam surface 68 will cause the two members to be drawn tightly together and accidental separation will be avoided. To further assure against accidental separation, the bail 60 is provided with an opening 72 registerable with an opening formed in the cam 70 to receive a locking pin 74 having a threaded end 76 for cooperation with a thread formed in the registering opening provided by the cam.

Other specific forms of clamping members may be employed but regardless of their form they will always preferably lie within the circumscribing prism of the container in their operative positions and within the projections of the side walls of the container members when the members are nested.

The closed ends 24 of the members are provided with recesses 78, those formed in the lower members 22 receiving supporting legs 80 and those formed in the upper member 20 registering with the legs 80 in their extended positions. As depicted in FIG. 9, journals 82 will be secured to the closed ends 24 of the lower members 22 by welding or the like to receive shafts 84 for rotation wherever the legs 80 can be rotated from the extended positions depicted in FIGS. 1, 3 and 9 to retracted positions in which they will lie entirely within the recesses 78 so that the closed ends 24 of the lower members can then lie in direct contact with a horizontal surface. When the legs 80 are extended they adapt the containers to be handled readily by means of a fork lift or pallet truck. Each leg includes a sleeve 86 secured to the shaft 84 integral with a pair of arms 88 to which a foot 90 is connected by a tubular pivot pin 92. The sleeve 86 is provided with a slot 94 to receive a detent 96 in the retracted position of the leg and a slot 98 for the reception of the same detent in the extended position of the leg. As shown in FIG. 8, journals at each pair of corners are aligned so that the shafts 84 of pairs of legs can be interconnected by a rod 100 whose threaded end carries a locking nut 102 so that a pair of legs can be actuated together from one side of the container. Each detent 96 is adapted to be received through a slot formed in a guide block 104 suitably secured to the closed base of each lower member 22 adjacent each sleeve 86 to assure registry with the slots 94 and 98. Also secured to the closed base of each lower member 22 by means of pivot pins 106 are a pair of links 108 on which the detents 96 are suitably mounted. The links 108 are interconnected by a pin 110 and a slot 112 so that when one of the links is moved to advance its detent 96 towards the sleeve 86, the other link will cause its detent 96 to be moved similarly with respect to its sleeve 86 thereby rendering it feasible to effect latching of each individual leg of a pair of legs from one side of the container. If desired, it may be sufficient to latch only one leg of each pair since the other leg is carried by the same rod 100 so that latching of one would tend to restrain the other as well. The details of the leg operating and latching arrangements have been depicted only in FIGS. 8 and 9 for purposes of clarity.

These legs are rendered retractable for economy in storage and transportation space which is particularly important on shipboard and to lower the center of gravity for stability.

The closed end 24 of the upper member is provided with a threaded plug or other closure 112 for filling operations. At one corner of the closed base of the closed base of the upper member 24 there is also provided a threaded opening to receive a plug or valve 114 which may serve as a vent or as a pressure inlet port to assist in the expulsion of the contents from the container. One corner of the closed end of the lower member 22 is truncated and defines an outlet port 116 fitted with a closure 118 which may assume the form of that disclosed in copending application Serial No. 93,520, filed March 6, 1961, now Patent

No. 3,140,793, for cooperation with a penetrating member used to fracture a diaphragm or otherwise break a seal.

It will be noted that the overall length of each peripheral flange 40 parallel to the axis of symmetry of its respective member 20 or 22, is equal to the length of each stepped section 32, made up of the portions 34 and 36, measured parallel to the same axis. Accordingly, when the members are arranged in nested relationship as depicted in FIG. 4, the peripheral flanges contact one another, maintaining the stepped sections in mutually spaced relationship and serving to protect the thinner portions of the members which are more susceptible to damage.

In view of the great strength and rigidity achieved by the present construction, the use of aluminum and its alloys as the principal material composing the members is not only feasible, but, because of its relatively low specific gravity, highly desirable. Where weight is not an important factor, other construction materials can, of course, be employed.

Whereas only one form of the invention has been described with reference to the accompanying drawings, a number of variations will suggest themselves to those skilled in the art and will fall within the scope of the appended claims.

I claim:

1. A container comprising two readily separable nestable members each having side walls extending axially from a closed base to a relatively larger open base each having substantially rectangular cross sections parallel to said bases, means carried by said open bases providing interengaging radial surfaces relatively supporting said members with their proximate side walls in spaced relationship when said members are nested, said side walls containing stepped prismatic peripheral sections, said larger open bases terminating in complementary sealing surfaces and carrying cooperating clamping elements.

2. A container according to claim 1 wherein said stepped sections have substantially equal dimensions axially of said container.

3. A container according to claim 1 wherein said stepped sections have substantially equal dimensions transversely of said container.

4. A container according to claim 1 wherein each of said open bases terminates in a peripheral rim having an axial dimension substantially equal to that of one of said stepped sections.

5. A container according to claim 1 wherein said stepped sections include pyramidal wall portions.

6. A container comprising two nestable members each having side walls comprising substantially uniform steps extending from a closed base to a relatively larger open base and each having substantially rectangular cross sections parallel to said bases, said open bases terminating in peripheral rims defining cooperating plug and socket members respectively, each of said rims having an axial dimension substantially equal to that of one of said steps, said rims providing interengaging radial surfaces relatively supporting said members with their proximate side walls in spaced relationship when said members are nested, one of said members containing a peripheral recess, and a deformable gasket disposed in said recess and extending peripherally therefrom for sealing engagement with the other of said members.

7. A container according to claim 6 wherein said recess is formed in said plug member.

8. A container according to claim 6 wherein said recess provides a surface composed of rectilinear elements extending axially of said container.

9. A container according to claim 6 wherein said gasket includes a plurality of peripherally extending sealing elements.

10. A container according to claim 6 wherein said gasket is elastomeric.

11. A container comprising two nestable members each of substantially rectangular cross section and each having side walls extending from a closed base to a relatively larger open base, a substantially rectangular reinforcing flange disposed at each open base, and cooperating clamping members carried by said flanges respectively, said clamping members having interengaging positions lying within a right rectangular prism having a cross section substantially coextensive with said flange.

12. A container according to claim 11 wherein said cooperating clamping members are disposed at the corners respectively of said flanges.

13. A container according to claim 11 wherein said cooperating clamping members are cams and levers respectively.

14. A container according to claim 11 wherein said cooperating clamping members are provided with positive locking means.

15. A container according to claim 11 wherein said cooperating clamping members provide eyes.

16. A container comprising two readily separable nestable members each of substantially rectangular cross section and each having side walls extending from a closed base to a relatively larger open base, said closed base of one member having corners each providing a recess, and a relatively movable supporting leg pivotally connected to the closed base of said one member adjacent to each of its corners each said leg having smaller dimensions than its respective recess for reception entirely within its respective recess whereby the closed base will bear directly on a supporting surface.

17. A container according to claim 16 wherein said legs are adjustable in pairs relative to the closed base to which they are connected.

18. A container according to claim 16 wherein each said closed base is recessed in registry with said legs.

19. A container according to claim 16 wherein said legs and closed base to which they are connected are provided with locking means to maintain them in a fixed relative position.

20. A container according to claim 1 wherein said members have curved corners joining adjacent walls thereof.
